[57] CLAIM

The ornamental design for the handle, as shown and described.

DESCRIPTION

FIG. 1 is a perspective view of the handle showing my new design;

FIG. 2 is a top plan view thereof;

FIG. 3 is a bottom plan view thereof;

FIG. 4 is a side elevation view thereof, the opposite side being identical;

FIG. 5 is a front elevation view thereof; and,

FIG. 6 is a rear elevation view thereof.

The peeler is shown in broken lines for illustrative purposes only and forms no part of the claimed design.
